Des. 216,501
Patented Jan. 27, 1970

216,501

NURSING HOME BUILDING

Jack E. Phillips, Warren, Ohio, assignor to Gillette
National Nursing Homes, Inc., Warren, Ohio, a corporation of Ohio

Filed May 31, 1968, Ser. No. 12,168

Term of patent 14 years

Int. Cl. D25—04

The rear side of the structure is substantially similar to the front side shown in FIGURE 1.

I claim:

The ornamental design for a nursing home building, as shown and described.
